(57) **CLAIM**

The ornamental design for a waterproof phone case, as shown and described.

DESCRIPTION

FIG. 1 is a front elevational view of a waterproof phone case showing my new design;

FIG. 2 is a rear elevational view thereof;

FIG. 3 is a left side view thereof;

FIG. 4 is a right side view thereof;

FIG. 5 is a top plan view, in enlarged scale, thereof;

FIG. 6 is a bottom plan view, in enlarged scale, thereof;

FIG. 7 is a top, front, right side perspective view thereof; and,

FIG. 8 is a bottom, rear, left side perspective view thereof. The broken lines, and unshaded areas bounded by broken lines, depict unclaimed portions of the waterproof phone case.
